CLAIM

The ornamental design for a container lid, as shown and described.

DESCRIPTION

FIG. 1 is a top perspective view of a container lid showing our new design;

FIG. 2 is a front side view of a container lid;

FIG. 3 is a back side view of a container lid;

FIG. 4 is a top side view of a container lid;

FIG. 5 is a bottom side view of a container lid;

FIG. 6 is a top perspective view of a container lid with a detachable umbrella portion in a detached orientation; and, FIG. 7 is a bottom perspective view of a container lid.

The broken lines in the drawings showing elements of the container lid represent unclaimed portions of the container lid and form no part of the claimed design.

1 Claim, 6 Drawing Sheets
